CLAMP APPLYING TOOL

Samuel Isaac Petrie, Mount Sidney, Va.

Application November 18, 1943, Serial No. 510,807

6 Claims. (Cl. 81—3)

This invention relates to certain new and useful improvements in clamp applying tools and more particularly to that type of tool adapted for closing and holding a clamp in such closed condition while applying a lock device to the clamp for holding the same in clamping engagement with the object or work to which it is applied.

An important object of the invention is to provide a clamp applying tool especially designed for the application of clamps incident to airplane motor mounts and wherein the clamps are employed for anchoring cables, conduits or the like to appropriate supports as well as for ground-ing purposes.

It is a further object of the invention to provide a clamp applying tool of the foregoing character embodying a pair of clamp-engaging jaws for moving the bolt-receiving apertured arms of a substantially cylindrical split clamp into juxtaposition for the reception of a retaining nut and bolt combination through said apertured arms combined with a clamp engaging shoe for holding the clamp rigidly supported within the tool, with devices for restraining the tool from releasing movement relative to the clamp so that the hands of the user are free for applying the nut and bolt combination.

A still further and important object of the invention is to provide a clamp applying tool, especially designed for airplane motor mounts and wherein the tool embodies a pair of cooperating clamp engaging jaw members with a clamp-engaging shoe adjustably supported on one of said jaw members whereby substantially cylindrical or other strap-like clamps of various sizes may be applied by a standard sized tool upon adjustment of the clamp-engaging shoe to cause the latter to forcefully engage the clamp when the clamp-engaging jaw members are in their closed positions.

Another object of the invention is to provide a clamp-applying tool for airplane motor mounts and the like wherein the tool embodies a pair of pivotally connected clamping jaws and a pair of pivotally connected handles for the operation of said jaws with a pivotal connection between the handles and jaws whereby the longitudinal axes of the handles may be disposed at an angle to the longitudinal axes of the jaws for the application of clamp members in areas that will not accommodate the full length of the tool.

With the above and other objects in view that will become apparent as the nature of the invention is better understood, the same consists in

the novel form, combination and arrangement of parts hereinafter more fully described, shown in the accompanying drawings and claimed.

In the accompanying drawings:

Figure 1 is a side elevational view of a clamp applying tool constructed in accordance with the present invention, the clamp gripping jaws of the tool being in their open position with a clamp resting on one of the jaws and adapted to be moved to its closed position,

Figure 2 is a top edge elevational view,

Figure 3 is a vertical longitudinal sectional view showing the jaws of the clamp in closed position and engaged with a larger clamp member than illustrated in Figure 1 with the adjustably mounted clamp-engaging shoe carried by one of the jaws engaged with the clamp,

Figure 4 is a detail sectional view taken on line 4—4 of Figure 3, showing the adjustable mounting for the clamp-engaging shoe,

Figure 5 is a cross-sectional view taken on line 5—5 of Figure 1, showing the pivotal connection between the handles of the tool,

Figure 6 is a detail sectional view taken on line 6—6 of Figure 3, showing the pawl and ratchet retaining device between the pivoted handles of the tool for retaining the clamping jaws in closed position,

Figure 7 is a fragmentary side elevational view, partly in section, of a modified construction showing the pivotally connected handles of the tool pivotally connected at their outer ends to the jaw members with relatively heavy spring devices associated with such pivotal connections for holding the jaw members in shifted angular positions relative to the longitudinal axes of the handles,

Figure 8 shows a modification of the pivotal connection between the handles and jaws wherein the connection of one handle with a jaw embodies tensioned coacting ribbed and grooved elements, and

Figure 9 is a plan view of the radially grooved washer forming a part of the connection between the handle and jaw member shown in Figure 8.

Referring more in detail to the accompanying drawings, there is illustrated a clamp applying tool, especially designed for the application of clamps incident to airplane motor mounts and said tool may be described as being of a plier type embodying a pair of handles 10 and 11 shown for purposes of illustration only as being of channel form in cross-section, with the open sides of the channels facing each other. A pair of lugs 12 project from the handle 10 intermediate

ate the ends thereof toward the handle 11, while a pair of coacting lugs 13 similarly projecting from the handle 11 are pressed towards each other as shown in Figure 5 for placement between the lugs 12 and through which lugs 12 and 13 a pivot pin 14 is mounted providing a pivotal connection between handles 10 and 11.

The handle 10 forwardly of the pivot 14 carries a rigid jaw 15 in line with said handle 10 and is of plate-like formation extending laterally of the jaw as illustrated. A standard 16 projects perpendicularly from the inner end of the jaw plate 15 substantially at right angles to the longitudinal axis of said plate, being positioned slightly forwardly of the forward end 15 of the handle 11 to provide a support for the movable jaw 17. As shown in Figure 3 the upper end of the standard is bifurcated or centrally cut away to provide side arms 18 between which the movable jaw 17 is positioned for pivotal mounting on the pin 19.

The forward end of the pivoted handle 11 is connected to the pivoted jaw 17 by means of a pair of side links 20 respectively disposed at the outer sides of said jaw and handle, being pivotally connected as at 21 at their lower ends to the handle 11 and pivotally connected as at 22 at their upper ends to the jaw 17. The jaw 17 carries a relatively large arcuate extension 23, the terminal end 23a of which is adapted for cooperation with the jaw plate 15 for closing the arms of a split clamp in a manner to be presently described. The arcuate extension 23 of the pivoted jaw 17 is normally influenced in a direction away from the jaw plate 15 by the relatively strong coil spring 24 interposed between the handles 10 and 11 inwardly of the handle pivot 14, and as shown in Figures 1 and 3 a pin 25 carried by each of the handles extends inwardly of the side flanges of the handles and into adjacent ends of the coil spring 24 with the latter bearing at its ends upon disk plates 26 mounted on the pins, each disk plate carrying a pair of diametrically opposite angularly directed lugs 26a disposed between the side flanges of the handles to retain the disk plates in position for a better setting of the spring 24. The tension of the spring 24 is operative for moving the handle 11 on its pivot pin 14 for forcing the forward end of the handle 11 toward the handle 10 and by its link connection 20 with the jaw 17, move the latter as described.

In the use of the tool, it is frequently desired to retain the jaw members 15 and 17 in clamp-engaging positions and to accomplish this object, a ratchet arm 27 is pivoted at one end as at 28 between the side flanges of the handle 10 inwardly of the coil spring 24 with the other end of the ratchet arm freely received within the side flanges of the handle 11 and extending in a direction toward the inner end of said handle. A pawl in the form of a plate 29 extends through an opening in the handle 11 and has a slotted opening 30 therein for the passage of the ratchet arm 27, the lower wall of the opening 30 being constructed to provide a pawl tooth for cooperation with the teeth of the ratchet arm 27. The opposite end of the pawl 29 carries a finger piece 31 extending outwardly of the handle 11. To maintain engagement of the pawl 29 with the ratchet arm 27, said pawl inwardly of said handle 11 has a spring connection 32 with said handle for normally positioning the tooth of the pawl at all times for engagement with the ratchet arm 27. The mounting of the pawl 29 within

5 the handle 11 is of a pivotal nature so that upon forward pressure on the finger-piece 31, the tooth of the pawl is disengaged from the ratchet arm 27 to permit the spring 24 to separate the clamp-engaging jaws 15 and 17.

The clamp applying tool is illustrated in Figure 3 in compressed engagement with a clamp, the latter as illustrated in Figures 1 and 3 being in the form of a substantially circular strap 33 carrying outwardly directed arms 34 and 35 that are apertured as at 36. The terminal end 23a of the arcuate extension 23 closes the normally open or separated arms 34 and 35 of the clamp with the tool jaws 15 and 17 retained in such clamping position by the pawl and ratchet devices associated with the handles 10 and 11. To hold the clamp 33 substantially rigidly positioned within the jaw members, a device is provided for engagement with the circular jaw portion 33 of the clamp and includes a pair of forwardly arcuate side arms 37 pivoted at their lower ends as at 38 at opposite sides of the standard 16 and inner end of the jaw plate 15, an arcuate shoe plate 39 connecting the side arms 37 as shown in Figures 1 and 3 with said arms and shoe plate normally influenced in a pivotal direction of movement toward the inner ends of the handles 10 and 11 by means of a coil spring 40 anchored at one end as at 41 to the handle 10, while the other end is anchored as at 42 to one of the side arms 37. An adjustably mounted device is associated with the pivoted jaw 17 and engageable with the shoe plate 39 for adjusting the normal position of said arms 37 and shoe plate 39 so that when the clamp engaging jaws are closed as illustrated in Figure 3, the shoe plate 39 will be engaged with the clamp strap 33 for holding the clamp rigidly positioned within the jaw members. The adjusting device comprises a rectangular frame having side bars 43 straddling the pivoted jaw 17 and end bars 44 and 45, the latter carrying an extension foot 46 freely engaged with the shoe plate 39. A screw 47 of a desired pitch to effect rapid adjustment is threaded through the pivoted jaw 17 with its outer end swiveled as at 48 in the end bar 45, the other end of the screw 47 rotatably extending through an opening in the end bar 44 and carrying an operating head 49. As a standard sized tool may be employed for the application of clamps of different sizes, such as illustrated in Figures 1 and 3, the normal position of the shoe plate 39 is adjusted so that when the clamping jaws are in the closed position illustrated in Figure 3, for moving the arms 34 and 35 of a clamp 33 into juxtaposition, the shoe plate 39 will be positively engaged with the loop portion of the clamp 33 for holding the same rigidly supported, one of the side bars 43 as shown in Figure 1 of the shoe plate adjusting device is graduated as at 50 while the carrying jaw 17 carries a cooperating indicator arrow 51. The graduations may be so defined as to normally position the shoe plate 39 for proper engagement with the particular size of clamp being applied by the tool.

From the above detailed description of the invention it is believed that the construction and operation thereof will at once be understood, it being noted that a standard sized tool may be employed for the application of clamps of different sizes. With the tool holding the clamp in closed position as shown in Figure 3, the pawl and ratchet devices associated with the handles 10 and 11 restrain the latter from moving on their

pivotal connection 14 so that the hands of the operator are free for passing a nut and bolt combination through the apertures 36 of the clamp arms 34 and 35. Should the openings 36 fail to register when the clamp arms are closed, an instrument of any appropriate character may be inserted through said openings to bring them into true registry. Also, with the unsupported tool holding the clamp in closed position, the hands of the operator are free for performing other services in connection with the clamp, such as engaging the extension arms of another clamp with the nut and bolt combination of the aforesaid anchored clamp or for the mounting of grounding wires and other purposes. Forward pressure on the fingerpiece 31 of the pawl will release the latter from the ratchet arm 27 and permit disengagement of the tool from the mounted clamp.

In applying clamps for airplane motor mounts, it frequently occurs that the particular location for the mounting of a clamp will not accommodate the full length of a clamp applying tool and to compensate for such work, the present invention further embodies a clamp applying tool, the structure of which embodies clamping jaws to which a pair of pivotally connected handles are pivotally attached so that the longitudinal axis of the handles may be placed at different angles relative to the longitudinal axis of the pivotally connected clamping jaws to permit the clamping jaws to be moved into a restricted space with the pivoted operating handles therefor disposed at an appropriate angle to the jaws. One form of such pivotal connection between the handles and jaws is illustrated in Figure 7 wherein the jaws 15 and 17 as illustrated in Figures 1 to 6 carry stub extensions 15a and 17a, each stub extension carrying a screw pin 22a directed towards each other with a ball 20a received in a socket 21a in adjacent ends of the handles 10a and 11a to form a universal mounting; relatively heavy coil springs 52 are interposed between the stub extensions 15a and 17a and the adjacent handle so that when the handles and jaws are relatively shifted, they will retain such adjusted positions. The spring 40a is disposed between jaw 17 and a side arm 37.

Another form of adjustment to vary the angularity between the jaws and handles is illustrated in Figures 8 and 9 wherein the stub extensions 15b and 17b of the jaws carry pin extensions 53 and 54, each pin extension carrying a ball 20b for reception in a socket 21b in adjacent ends of the handles 10b and 11b providing a universal connection. The connection associated with the stub extension 17b has the pin 54 rectangular in cross-section for the reception of a concaved washer plate 55, the inner face of which is radially grooved as at 56 for the reception of ribs 57 rising from the adjacent arcuate surface of the bearing end of the handle 11b, a coil spring 58 being interposed between the stub extension 17b and washer plate 55 for holding the pivoted jaw members and handles in their angularly adjusted positions.

While there are herein shown and described the preferred embodiments of the invention, it is nevertheless to be understood that minor changes may be made therein without departing from the spirit and scope of the invention as claimed.

I claim:

1. In a tool for attaching a clamp to an object, wherein the clamp is of strap-like circular form

with normally spaced apertured arms carried by the clamp for the attachment of holding means, said tool comprising a rigid jaw member and a cooperating jaw member pivoted to the rigid jaw member and pivotally connected handles attached to the jaw members adapted to move the pivoted jaw member toward the rigid jaw member and into engagement with the adjacent clamp arm for juxtaposing the clamp arms for attachment of the holding means, a shoe plate pivotally interposed between said jaws, means adjustably carried by the pivoted jaw member and operatively engaged with the shoe plate for moving with the latter into engagement with the clamp in spaced relation to the clamp arms for holding the clamp rigidly supported in the jaw members.

2. In a tool for attaching a clamp to an object, wherein the clamp is of strap-like circular form with normally spaced apertured arms carried by the clamp for the attachment of holding means, said tool comprising a rigid jaw member and a cooperating jaw member pivoted to the rigid jaw member and pivotally connected handles attached to the jaw members adapted to move the pivoted jaw member toward the rigid jaw member and into engagement with the adjacent clamp arm for juxtaposing the clamp arms for attachment of the holding means, a shoe plate pivotally interposed between said jaws, means adjustably carried by the pivoted jaw member and operatively engaged with the shoe plate for moving with the latter into engagement with the clamp in spaced relation to the clamp arms for holding the clamp rigidly supported in the jaw members.

3. In a tool for attaching a clamp to an object, wherein the clamp is of strap-like circular form with normally spaced apertured arms carried by the clamp for the attachment of holding means, said tool comprising a rigid jaw member and a cooperating jaw member pivoted to the rigid jaw member and pivotally connected handles attached to the jaw members adapted to move the pivoted jaw member toward the rigid jaw member and into engagement with the adjacent clamp arm for juxtaposing the clamp arms for attachment of the holding means, a shoe plate pivotally interposed between said jaws, means adjustably carried by the pivoted jaw member and operatively engaged with the shoe plate for moving with the latter into engagement with the clamp in spaced relation to the clamp arms for holding the clamp rigidly supported in the jaw members, and coacting means carried by the handles for holding the jaw members in clamp engaging position.

4. In a tool for attaching a clamp to an object, wherein the clamp is of strap-like circular form with normally spaced apertured arms carried by the clamp for the attachment of holding means, said tool comprising a rigid jaw member and a cooperating jaw member pivoted to the rigid jaw member and pivotally connected handles attached to the jaw members adapted to move the pivoted jaw member toward the rigid jaw member and into engagement with the adjacent clamp arm for juxtaposing the clamp arms for attachment of the holding means, a shoe plate pivotally interposed between said jaws, means adjustably carried by the pivoted jaw member and operatively engaged with the shoe plate for moving with the latter into engagement with the clamp in spaced relation to the clamp arms for holding the clamp rigidly supported in the jaw members, means for normally influencing the pivoted shoe plate away from the outer end of the rigid jaw member and said adjustable means being operative for limiting retracting movement of the shoe plate and normally setting the shoe plate in positions for clamps of different diameters whereby the shoe plate is positively engaged with a clamp when the pivoted jaw moves the clamp arms into juxtaposition.

5. In a tool for attaching a clamp to an object, wherein the clamp is of strap-like circular form with normally spaced apertured arms carried by the clamp for the attachment of holding means, said tool comprising a rigid jaw member and a cooperating jaw member pivoted to the rigid jaw member and pivotally connected handles attached to the jaw members adapted to move the pivoted jaw member toward the rigid jaw member and into engagement with the ad-

jaçent clamp arm for juxtaposing the clamp arms for attachment of the holding means, a shoe plate pivotally interposed between said jaws, means adjustably carried by the pivoted jaw member and operatively engaged with the shoe plate for moving with the latter into engagement with the clamp in spaced relation to the clamp arms for holding the clamp rigidly supported in the jaw members, co-acting means carried by the handles for holding the jaw members in clamp engaging position, means for normally influencing the pivoted shoe plate away from the outer end of the rigid jaw member and said adjustable means being operative for limiting retracting movement of the shoe plate and normally setting the shoe plate in positions for clamps of different diameters whereby the shoe plate is positively engaged with a clamp when the pivoted jaw moves the clamp arms into juxtaposition.

5. In a tool for attaching a clamp to an object, a jaw member and a handle rigid therewith, a second jaw member pivotally mounted on the rigid jaw member and being of arcuate form with the outer terminal end thereof adapted to be moved into proximity of the other end of the rigid jaw member, a second handle pivotally mounted on the rigid handle, link connections between the outer end of the pivoted handle and the inner end of the pivoted jaw, means for holding the pivoted jaw in closed clamp-engaging

position, a clamp engaging shoe plate pivotally interposed between said jaws, and graduated adjustable means carried by the pivoted jaw engaged with the shoe plate for normally positioning the shoe plate for engagement with a clamp when the outer terminal end of the pivoted jaw member is disposed adjacent the outer end of the rigid jaw member.

6. In a tool for attaching a clamp to an object, a jaw member and a handle rigid therewith, a second jaw member pivotally mounted on the rigid jaw member and being of arcuate form with the outer terminal end thereof adapted to be moved into proximity of the other end of the rigid jaw member, a second handle pivotally mounted on the rigid handle, link connections between the outer end of the pivoted handle and the inner end of the pivoted jaw, means for holding the pivoted jaw in closed clamp-engaging position, a clamp engaging shoe plate pivotally interposed between said jaws, and graduated adjustable means carried by the pivoted jaw engaged with the shoe plate for normally positioning the shoe plate for engagement with a clamp when the outer terminal end of the pivoted jaw member is disposed adjacent the outer end of the rigid jaw member and a spring interposed between the handles for normally holding the jaw members in open position.

SAMUEL ISAAC PETRIE.
